WIRE CLAMP

William G. Fotsch, Chicago, Ill., assignor to Reliable Electric Co., Chicago, Ill., a corporation of Illinois

Application December 3, 1934, Serial No. 755,790

1 Claim. (Cl. 173—263)

This invention relates to wire clamps and has for its principal purpose the provision of a clamp of this character which can be utilized to clamp two wires together either stranded or not stranded in such fashion as to make a good electrical contact and a strong mechanical connection.

More specifically the invention contemplates the provision of a two piece clamp consisting of a U-shaped member having aligned openings in the legs thereof to receive the wires to be clamped and a screw or clamping member engaging the wires in such fashion as to prevent lateral escape of the strands.

Other and more specific objects and advantages of the invention will appear as the description proceeds in connection with the accompanying drawing wherein the preferred form of the invention is shown. It is to be understood, however, that the description and drawing are illustrative only and not to be taken as limiting the invention except in so far as it is limited by the claim.

In the drawing—

Fig. 1 is a side elevation of the clamp as applied to the connection of two wires;

Fig. 2 is a section on the line 2—2 of Fig. 1; and

Fig. 3 is a bottom view looking upward at the clamp as it is shown in Fig. 1.

Referring now in detail to the drawing, my improved clamp consists of a U-shaped member 5 having the base portion 6 reenforced by the flange 7 and provided with a screw threaded aperture at 8 to receive the set screw 9.

The U-shaped member 5 has the opposed parallel portions 10 and 11 provided with elongated apertures as shown more clearly at 12 in Fig. 2 for receiving the conductors or wires such as 13 and 14. Each of the legs 10 and 11 has formed thereon the lateral flanges 15 and 16 which flanges are extended toward each other a substantial distance from the legs 10 and 11 so as to make the gap therebetween less than the diameter of the set screw 9 or at most, at least as small as the diameter of the set screw 9.

There is another relation between the set screw 9 and the members 15 and 16 which is also of importance and that is that the width of the opening 12 is preferably substantially the diameter of the set screw 9. Therefore, if a wire is clamped down against the flanges 15 and 16, there is no chance for lateral escape of stranded wires, for example by spreading. This is because of the fact that the space in which the wires may spread under pressure is smaller than the diameter of the screw which furnishes the pressure.

Furthermore, this construction while permitting a slight bending of the wires at the center to give a strong mechanical hold or grip of one wire upon the other also provides long surface 15 contacts or support of the wires by means of the legs 10 and 11 and their flanges 15 and 16 thus making a good electrical joint as well as a strong mechanical joint.

From the above description, it is believed that 20 the construction and advantages of this device will be clear to those skilled in this art.

Having thus described one specific form of my invention what I claim as new and desire to secure by Letters Patent is:

A two piece clamp comprising a U-shaped member having aligned elongated slots running lengthwise in the legs of said member to receive the wires to be clamped and to position them substantially in parallelism, a clamping screw threaded through the base for pressing together the wires threaded through said slots, and means on the legs to provide side support for said wires when they are clamped together, said means comprising U-shaped flanges at the edges of said 35 elongated slots and projecting inwardly toward each other from said legs and spaced apart a distance less than the diameter of said screw, the diameter of said screw being at least equal to the width of said slots whereby to prevent lateral escape of said wires when they are pressed together by said screw.

WILLIAM G. FOTSCH.
